(No Model.)

E. T. STARR.

BAYONET.

No. 269,547.

Patented Dec. 26, 1882.

*E. T. Starr
Inventor
by his Attorney
Mount Brown*

UNITED STATES PATENT OFFICE.

EBEN T. STARR, OF NEW YORK, N. Y.

BAYONET.

SPECIFICATION forming part of Letters Patent No. 269,547, dated December 26, 1882.

Application filed March 1, 1882. (No model.)

To all whom it may concern:

Be it known that I, EBEN T. STARR, of the city and county of New York, in the State of New York, have invented certain new and useful Improvements in Bayonets, of which the following is a specification.

The invention consists in the combination, with the barrel and ramrod or wiping-rod of a fire-arm, of a bayonet provided with two parallel sockets, one of which is fitted to the barrel and the other of which receives within it the end of said ramrod or wiping-rod.

The invention also consists in the combination, with the band of a fire-arm forming the "tip" of the fire-arm, and having in its front a recess or cavity, of a bayonet having a socket fitted to the barrel and a projection adapted to enter said recess or cavity, and thereby prevent the turning of the socket upon the barrel.

The invention also consists in a novel construction and manner of securing the ramrod or wiping-rod used with said sword-bayonet.

In the accompanying drawings, Figure 1 represents a side view of my improved bayonet. Fig. 2 represents a longitudinal section of the muzzle portion of a fire-arm barrel and the hilt or socket portion of a bayonet fitted thereon, representing the said parts full size. Fig. 3 represents a transverse section on the dotted line *x x*, Fig. 2, looking in the direction indicated by the arrows; and Fig. 4 is a transverse section of the bayonet-hilt on the dotted line *y y*, Fig. 2.

Similar letters of reference designate corresponding parts in all the figures.

A designates the muzzle portion of the barrel of a fire-arm, and B designates the fore-stock.

C designates the band which forms the tip of the fire-arm, and which is recessed on the back or rear side at *a* to receive the end of the fore-stock.

D designates the bayonet, which is made in the form of a short sword, as clearly seen in Fig. 1, and the hilt portion of which is fitted to the barrel A. The bayonet is provided with a socket, D', which receives the barrel A, and with a second and smaller socket, D'', which is parallel with the socket D'. The two said sockets form a handle or hilt, which is adapted

to be grasped in the hand to enable the bayonet to be used effectively as a sword in case it be desirable.

E designates the wiping-rod, which is provided with a tubular end portion, E', and when it is not in use the rod passes through the said tubular portion, and is screwed into the front end thereof at *b*, while the opposite end of said tubular portion is furnished with a screw-thread, *c*, and may be screwed into the band C. When the wiping-rod is to be used the tubular end portion is unscrewed from the band C and from the end of the rod E, after which it is reversed in position and again screwed thereon, thus making the rod long enough for use. When the rod E is in the band C its front end is received within the socket D'' of the bayonet, and it will be seen that as the hilt of the bayonet receives both the barrel and rod E it will be prevented from turning on the barrel.

In the front side of the band C is a recess or cavity, *d*; and *e* designates a hub or projection which forms an extension of the socket D'', and which enters the recess or cavity *d* in the band C. The engagement of the hub or projection *e* with the recess or cavity *d* still further prevents the bayonet from turning on the barrel.

At the front end of the socket D'' is a catch for holding the bayonet on the barrel. This catch is composed of a lever, F, fulcrumed on a pin, *h*, and having a pin, *f*, which enters a recess, *g*, in the interior of the barrel. One arm of the lever F projects beyond the exterior wall of the socket D'', so that it may be operated by the finger to withdraw the pin *f* from the recess *g*, and the lever is acted upon by a spring, *i*, to hold the pin in engagement with the recess.

It will be observed that the bayonet is held against turning on the barrel independently of the pin *f*, and that the latter only serves to prevent the bayonet from being pulled off the barrel.

What I claim as my invention, and desire to secure by Letters Patent, is—

1. The combination, with the barrel and ramrod or wiping-rod of a fire-arm, of a bayonet provided with two parallel sockets, one of

which is fitted to the barrel and the other of which receives the end of said rod, substantially as herein described.

2. The combination, with the barrel of a fire-arm, and a band forming the tip and having a recess or cavity in its front side, of a bayonet provided with a socket fitting said barrel, and with a hub or projection adapted to enter said recess or cavity, substantially as herein described.

3. The combination of the barrel A, the band C, the rod E, and the tubular portion E', screwed upon the end of the rod and screwed into said band, and the bayonet D, provided with sockets D' D², substantially as herein described. 15

EBEN T. STARR.
